(57) **CLAIM**

The ornamental design for a dispensing cap, as shown and described.

DESCRIPTION

FIG. 1 is an isometric view of a dispensing cap showing my new design;

FIG. 2 is a top plan view thereof;

FIG. 3 is front elevational view thereof, the rear being a mirror image;

FIG. 4 is left side elevational view thereof, the right side being a mirror image; and,

FIG. 5 is a bottom plan view thereof.

The material container is shown in broken lines for illustrative purposes only and forms no part of the claimed design.
